(57) CLAIM

The ornamental design for the article holder, as shown and described.

DESCRIPTION

FIG. 1 is a perspective view of the article holder showing my new design;

FIG. 2 is a left side elevational view, the right side elevational view being identical;

FIG. 3 is a front elevational view thereof;

FIG. 4 is a rear elevational view thereof;

FIG. 5 is a top plan view thereof;

FIG. 6 is a bottom plan view thereof;

FIG. 7 is a perspective view showing use environment with the broken line representation of a long gun and support rail being for illustration only and forming no part of my design; and,

FIG. 8 is a side elevational view of a second embodiment being identical to the first embodiment except for the wider spacing between the front bracket and rear legs thereof.
